UNITED STATES PATENT OFFICE.

WILLIAM A. HARRIS, OF PROVIDENCE, RHODE ISLAND.

DASH-POT.

SPECIFICATION forming part of Letters Patent No. 469,697, dated March 1, 1892.

Application filed May 26, 1891. Serial No. 394,235. (No model.)

To all whom it may concern:

Be it known that I, WILLIAM A. HARRIS, of Providence, county of Providence, State of Rhode Island, have invented an Improvement 5 in Dash-Pots, of which the following description, in connection with the accompanying drawings, is a specification, like letters and figures on the drawings representing like parts.

This invention has for its object to provide 10 an improved dash-pot whereby the usual noise incident to operation of the same may be dispensed with.

Heretofore it has been common to provide 15 a communication between the cushioning-chamber of the dash-pot and the atmosphere by a lateral opening in the wall of the chamber itself or in the wall of the reservoir-chamber communicating therewith, the air being alternately drawn into the chamber and expelled 20 therefrom through this opening by the operation of the dash-pot, producing an objectionable whistling noise. In my experiments to overcome this objectionable feature I have discovered that the noise referred to 25 may be entirely avoided by providing the dash-pot with one or more exterior annular openings of considerable length, through which the air is drawn into and expelled from the cushioning-chamber of the dash-pot.

30 One part of this invention therefore consists of a dash-pot containing a cushioning-chamber and one or more exterior annular outlet-openings communicating with said cushioning-chamber, substantially as will be described.

35 Other features of this invention will be hereinafter described, and pointed out in the claims.

Figure 1 represents in elevation a dash-pot 40 embodying this invention; Fig. 2, a vertical section thereof; Fig. 3, a top or plan view of the lower stationary casting and base-plate, and Fig. 4, a modification to be referred to.

Figs. 1 to 3, inclusive, represent my invention as applied to one form of dash-pot, wherein the base-plate a is and may be of usual or desired shape, to which is secured by bolts or screws 5 (see dotted lines, Fig. 1) the lower stationary casting B , in which is formed 45 the central vacuum-cylinder b' , surrounded wholly or partially by the reservoir-chamber

b^2 , which latter at its upper end is provided with openings or ports b^3 (shown by dotted lines, Fig. 3) and closed by suitable valves b^4 . The regulating port or passage c , controlled 55 by an adjusting-screw c' , is also provided, through which the air is forced upon the descent of the dash-pot piston.

The movable casting D of the dash-pot is herein represented as provided with a central 60 piston d , fitted to move in the vacuum-cylinder b' , and an annular flange d' to co-operate with the stationary casting B to form a cushioning-chamber b^5 to cushion the movable casting when the same is drawn down. The 65 movable casting D is provided with a suitable wrist-pin d^2 , to which is jointed the actuating-rod. (Not shown.) The vacuum-cylinder b' is provided with a suitable valve v to maintain the vacuum therein. 70

Heretofore it has been customary to provide the chamber b^2 with openings drilled laterally through its side wall, through which the air is drawn into the chamber as the piston d and movable casting D are drawn up, 75 the air so drawn into the chamber being expelled again through the passage c and said openings when the said movable casting is released and returned to its normal position shown. This operation of drawing the air 80 into and expelling it from the chamber b^2 through said openings produces an objectionable whistling noise, and to obviate such noise I dispense with said openings, and in place thereof, as herein represented, extend 85 the chamber b^2 or a portion thereof to the bottom of the casting b and provide the same with an exterior annular outlet a^x , Fig. 1, of considerable length, extending wholly or partially around the exterior of the dash-pot, 90 said opening being herein represented as formed by raising the casting b from the base-plate a and supporting the said casting on washers a' of the requisite thickness. The annular opening a^x will preferably extend 95 substantially around the exterior of the dash-pot b on all sides and will provide such an opening for the passage of air to and from the cushioning-chamber that all noise or whistling will be entirely obviated. By employing washers a' of varying thickness the opening a^x may be so regulated as to produce the 100

best results; but instead of employing washers the base-plate *a* or casting *b* may be formed with bosses or raised seats to thereby leave an annular opening between the casting and base-plate. It is also evident that the exterior opening *a*^x may be formed in the casting *b* itself.

The exterior annular opening *a*^x, through which the air is expelled from the cushioning-chamber, is represented in Figs. 1 to 3, as leading to a reservoir-chamber, which latter opens into the cushioning-chamber; but I do not limit this invention to such construction, as the same may be embodied in any other form of dash-pot and produce a like effect.

In Fig. 4 I have represented another form of dash-pot, which does not include the reservoir-chamber, the exterior annular opening leading directly into the cushioning-chamber. Neither is this invention limited to a single annular opening, as a series of segmental or shorter openings may be employed with like result, the noiseless action of the dash-pot being effected by expelling the air therefrom through one or more long but comparatively thin or narrow openings rather than through one or more round or square openings.

I claim—

1. A dash-pot containing a cushioning-chamber and one or more exterior annular outlet-openings communicating with said cushioning-chamber, to operate substantially as described.
2. A dash-pot containing a cushioning-chamber, a reservoir-chamber communicating therewith, and one or more exterior annular outlet-openings for said reservoir-chamber, to operate substantially as described.

3. In a dash-pot, the combination, with a base-plate, of a stationary casting supported by said base-plate, with an opening between it and the base-plate, and a chamber in said casting communicating with said opening, substantially as described.

4. In a dash-pot, the combination, with a base-plate, of a stationary casting supported by said base-plate and containing a chamber and washers separating said base-plate and casting, substantially as described.

5. In a dash-pot, a base-plate, a stationary casting supported thereby and containing a vacuum-cylinder and a chamber provided with an annular outlet-opening, combined with a movable casting having a piston for said vacuum-cylinder and co-operating with said chamber to cushion the said movable casting when the same is drawn down, substantially as described.

6. In a dash-pot, a base-plate, a stationary casting supported thereby, with an opening between it and the said base-plate, a vacuum-cylinder in said casting, and a chamber in communication with said opening, combined with a movable casting having a piston for said vacuum-cylinder and co-operating with said chamber to cushion the said movable casting as the same is drawn down, substantially as described.

In testimony whereof I have signed my name to this specification in the presence of two subscribing witnesses.

WILLIAM A. HARRIS.
